Des. 204,364
Patented Apr. 12, 1966

204,364

RECEPTACLE FOR TOILET CLEANING SWAB OR THE LIKE

Leon M. Corning, Redwood City, Robert L. Friedenthal,
San Mateo, and Robert E. Sarafan, San Francisco,
Calif., assignors to Advance Chemical Company, San
Francisco, Calif., a corporation of California

Filed Nov. 13, 1964, Ser. No. 82,582

Term of patent 14 years

(Cl. D9—2)

Fig. 2.

Fig. 1.

Fig. 3.

Fig. 4.

FIG. 1 is a side elevational view of a receptacle for toilet cleaning swab showing our new design.

FIG. 2 is a top plan view thereof.

FIG. 3 is a bottom plan view thereof.

FIG. 4 is an end elevational view thereof as viewed from the right in FIG. 1.

FIG. 5 is an end elevational view looking from the left of FIG. 1 with the broken line portions being omitted.

The portions shown in broken lines are for illustrative purposes only.

We claim:

The ornamental design for receptacle for toilet cleaning swab or the like, as shown and described.
